UNITED STATES PATENT OFFICE.

ROBERT ALFORD, OF LENOIR CITY, TENNESSEE.

ENGINE PISTON.

Application filed October 19, 1922. Serial No. 595,500.

To all whom it may concern:

Be it known that I, ROBERT ALFORD, a citizen of the United States, residing at Lenoir City, in the county of Loudon and State of Tennessee, have invented certain new and useful Improvements in Engine Pistons, of which the following is a specification.

In the conventional type of combustion engine pistons, it is a well known fact that the piston lubricating oils have a tendency to pass upwardly beyond the piston rings carried by the piston for consequently adhering to the spark plugs and preventing 10 firing of the same and also creating carbon deposits within the combustion chamber, which action prevents the efficient operation of the engine, and oftentimes necessitates a comp'ete overhauling of the same. 15 It is therefore the primary object of the present invention to provide an improved form of piston, wherein any excess lubricants that would otherwise tend to seep upwardly past the rings will be conveyed 20 downwardly into the usual oil groove formed on the piston, whereby the above mentioned objections are effectively overcome.

A further object of the invention resides 25 in the provision of such an engine piston that may be manufactured without any increase in expense over those now almost universally employed.

With the above and other objects in view, 30 as the nature of the invention is better understood, the same comprises an extremely simple construction of engine piston, hereinafter more fully described and shown in the accompanying drawings, forming a part 35 of the present application.

In the drawings:—

Figure 1 is a side elevational view of a piston constructed in accordance with the present invention.

Figure 2 is a vertical cross sectional view upon the lines 2—2 of Figure 1.

Figure 3 is a fragmentary vertical section upon the line 3—3 of Figure 1, and looking in the direction of the arrows, and

Figure 4 is a fragmentary sectional view upon the line 4—4 of Figure 1, and looking downwardly in the direction of the arrows.

Briefly described, the invention contemplates the provision of an engine piston having the usual upper set of ring grooves and the lower oil groove, novel means being

provided between the lower oil groove, and the adjacent ring groove for conveying any oil, that would tend to escape beyond the ring grooves, downwardly to the oil groove. 60 This novel means merely includes the provision of a plurality of other grooves or channels diagonally arranged upon the face of the piston, and between the lower ring groove and oil groove in a manner herein- 65 after more fully described.

Having particular reference to the several views, there is shown a usual piston 1, having a set of upper ring grooves 2, and a lower oil groove 3, and aligned annular 70 apertures 4 in the side wall thereof, the provision of which will be readily apparent.

Arranged upon the face of the piston 1, and at opposite sides of the annular apertures 4, are a pair of oil grooves or channels 75 5, diagonally arranged in opposite directions upon the face of the piston, the upper ends thereof connecting as shown. The connecting ends of these grooves or channels are disposed at a point slightly beneath the 80 bottom wall of the lower ring groove 2, this bottom wall being transversely slotted as at 6 for establishing communication between the upper connecting ends of the grooves, and a relatively small bore 7, extending 85 through the wall of the piston, for allowing some of the excess oil to pass therethrough and thence to flow downwardly upon the inner face of the piston wall.

As above stated, the grooves 5 are arranged 90 diagonally in opposite directions upon the wall of the piston, and each of these grooves are so formed within the piston as to appear hooked shaped in cross section as shown in Figure 3, thereby constituting a series of 95 diagonally arranged pockets or oil channel ways. The hooked or curved end of the grooves effect the bottom wall thereof, and is designated by the numeral 8. The inner wall 9 of the grooves are substantially elongated with respect to the opposite outer wall 10, and is so cut within the piston as to converge inwardly with respect to the longitudinal axis of the wall thereof. The upper edge of the outer wall 10 of the grooves will 100 present a knife-like edge to the wall of the cylinder for scraping the oil therefrom, whereby the same will be received within the diagonally arranged pockets or channel ways of the piston to be conveyed downwardly into the oil groove 3. 105

From the above description, it will be

readily apparent that the lubricant tending to work its way upwardly upon the wall of the piston, will be effectively caught within the said diagonally arranged grooves, where-
5 by the same will be conveyed downwardly into the usual oil groove 3. A portion of the excess oil will pass along the trans-
verse channel 6 at the upper connecting ends of the adjacent grooves for exit through
10 the small bore 7, and thence downwardly within the piston. It will of course be readily apparent, that the lower end of each of the diagonal grooves 5 communicate with the oil groove 3 formed in the piston for
15 purpose previously described.

Even though I have herein set forth the preferred embodiment of the present in-
vention, it is nevertheless to be understood that I do not wish to limit myself to this
20 exact structure, as minor changes may be

made therein without departing from the spirit and scope of the invention as claimed.

What is claimed as new is:—

In engine pistons of the type including upper ring grooves and a lower oil groove, 25 a pair of diagonally arranged channel ways formed upon the opposite sides of the piston wall, the channel way of each pair arranged in opposite directions and establishing communication at their upper ends, the said 30 piston wall having a bore therethrough communicating with the upper ends of the channel ways for allowing a portion of the excess oil to pass interiorly of the piston and other excess oil being received within 35 the said channel ways whereby the same is conveyed to the oil groove within the piston.

In testimony whereof I affix my signature.

ROBERT ALFORD.
